(57) **CLAIM**

The ornamental design for an electrical adapter, as shown.

DESCRIPTION

FIG. 1 is a front elevational view of an electrical adapter showing my new design;

FIG. 2 is a rear elevational view thereof;

FIG. 3 is a top plan thereof;

FIG. 4 is a bottom plan view thereof;

FIG. 5 is a right side view thereof, the left side view being a mirror image of the right side view;

FIG. 6 is a perspective view thereof; and,

FIG. 7 is another perspective view thereof.
